UNITED STATES PATENT OFFICE.

OSWALD LÄTZSCH, OF ZSCHERNITZSCH, AND OTTO LÄTZSCH, OF LINDENTHAL,
GERMANY.

APPARATUS FOR SWEEPING CHIMNEYS.

1,054,924.

Specification of Letters Patent.

Patented Mar. 4, 1913.

Application filed June 20, 1912. Serial No. 704,818.

To all whom it may concern:

Be it known that we, OSWALD LÄTZSCH, a subject of the Duke of Saxe-Altenburg, residing at Zschernitzsch, in the Duke-dom of Saxe-Altenburg, Germany, and Otto LÄTZSCH, a subject of the King of Saxony, residing at Lindenthal, in the King-dom of Saxony, Germany, have invented certain new and useful Improvements in 10 Apparatus for Sweeping Chimneys, of which the following is a specification.

This invention relates to an apparatus for sweeping chimneys of that type in which the sweeping body proper is thrown up in the chimney by the detention of a spring so that when it comes down again the soot is scraped off the walls.

In the accompanying drawings the invention is shown by way of example.

20 Figure 1 is a longitudinal section of the casing for the spring. Fig. 2 is a plan view of Fig. 1. Fig. 3 shows the casing with the spring in elevation and the sweeping body proper in section. Fig. 4 is a plan view of 25 Fig. 3.

The casing for the spring consists of a rectangular foot *b* which corresponds in size with the inner width of the chimney and further of a rectangular casing *c* mounted upon said foot. In the casing *c* an iron rod *e* is fixed upon the bottom of the casing by means of a nut *d*. The upper end *f* of the rod *e* is threaded and a hand wheel *g* is screwed upon this threaded part which 30 serves for compressing the spiral spring *h*. In the casing *c* a slide *i* is arranged which, after the hand wheel has been screwed down to the upper edge of the slide, is pushed into the casing *c* in order to maintain the spring 35 *h* compressed, whereupon the hand wheel *g* is screwed off the iron rod *e*. The slide *i* has a slot *k* the inner width of which corre-

sponds to the diameter of the iron rod *e*. The slide *i* is guided in grooves *l* and *m* of the front and back walls of the casing *c*. 45 After the removal of the hand wheel the sweeping body *n* (Fig. 3) is loosely placed upon the iron rod *e* so that when the slide is pulled out of the casing the spring distends and throws the sweeping body *n* up 50 in the chimney. When the sweeping body *n* comes down its bristles *p* rub along the walls of the chimney and scrape off the soot.

The upward movement of the sweeping body proper is limited by a rope *q* fixed 55 with one end to said sweeping body and by one of a certain number of eyes *r* to the casing *c*. The eyes *r* bear inscriptions indicating the height of the throw of the sweeping body proper.

We claim:

An apparatus for sweeping chimneys comprising in combination a casing having guide grooves in the inner surfaces of the front and rear wall, a slide guided in said 65 grooves, a rod vertically fixed in the bottom of said casing, and having an upper threaded part, a spiral spring surrounding the lower end of said rod, said slide having engagement with said rod when in inward position to hold said spring compressed, and a brush having outwardly extending fiber and a bore loosely fitting over the top of said rod, in position to be projected upward by said spring when it is released, 70 substantially as described and shown and for the purpose set forth.

In witness whereof we have hereunto set our hands in the presence of two witnesses.

OSWALD LÄTZSCH.
OTTO LÄTZSCH.
